UNITED STATES PATENT OFFICE.

GUSTAF A. ERICKSON, OF MINNEAPOLIS, MINNESOTA, ASSIGNOR TO
JOHN E. ERICKSON, OF ST. PAUL, MINNESOTA.

ARTIFICIAL LEG.

No. 838,779.

Specification of Letters Patent.

Patented Dec. 18, 1906.

Application filed September 10, 1906. Serial No. 333,952.

To all whom it may concern:

Be it known that I, GUSTAF A. ERICKSON, a citizen of the United States, residing at Minneapolis, in the county of Hennepin and 5 State of Minnesota, have invented certain new and useful Improvements in Artificial Legs; and I do hereby declare the following to be a full, clear, and exact description of the invention, such as will enable others 10 skilled in the art to which it appertains to make and use the same.

My invention relates to artificial legs, and has for its object to improve the same in the several particulars hereinafter noted.

15 The invention is illustrated in the accompanying drawings, wherein like characters indicate like parts throughout the several views.

Figure 1 shows the complete artificial leg 20 in side elevation. Fig. 1^a is a side elevation of the slip-socket removed from working position. Fig. 2 is a horizontal section taken on the line x² x² of Fig. 1. Fig. 3 is a detail in vertical section taken on the line x³ x³ of 25 Fig. 2. Fig. 4 is a section taken on the line x⁴ x⁴ of Fig. 1. Fig. 5 is a detail in side elevation with some parts broken away and others sectioned, showing one of the spring-cushion devices. Fig. 6 is a view corresponding to Fig. 5, illustrating a slightly-modified form of the spring-cushion; and Fig. 7 is a view partly in horizontal section 30 on the line x⁷ x⁷, Fig. 1, but with some parts left in full and with some parts broken away.

35 The numeral 1 indicates the lower leg-section of the artificial limb, the same having the usual foot 2.

The numeral 3 indicates the thigh-socket, which is of the usual construction and is 40 connected to the leg-section 1 by a pair of metallic thigh-straps 4, rigidly secured to said members, with its sections hinged at 5 to afford a knee-joint.

45 The numeral 6 indicates the so-called "slip-socket," which at its sides is provided with channeled guides that embrace the edges of the lower sections of the thigh-straps 4 and is guided for vertical movements thereby. The said channeled guides on the 50 sides of the slip-socket are lined with buckskin or similar material, (indicated at 7,) and the bottoms of the said channels at intervals are formed with transverse grooves, into which the said buckskin lining is adapted to

be pressed by the transverse bars 8 of a skeleton metal frame made up of the said bars 8 and integrally-cast side bars 8^a. The side bars 8^a overlap the outer surface of the slip-socket and are secured thereto by screws, rivets, or other suitable devices. 55

By means of the skeleton frame the buckskin lining 7 is tightly clamped in working position, and the bars 8 are pressed below the surface of the buckskin, which extends between said bars. The side bars 8^a are 60 notched at 8^b, so that the buckskin projects therethrough at the sides of the channel for engagement with the edges of the co-operating thigh-strap 4. The lower sections of the thigh-straps at their inner faces and at their 65 edges are therefore caused to rub directly against the buckskin, thereby making the device noiseless in its sliding action and affording a friction device which acts as a spring-dampener to retard the movements 70 of the socket-supporting springs or cushions which are interposed between the leg-section 1 and the slip-socket 6 and which will now be described. The preferred form of these spring-cushions is illustrated in Figs. 2 to 5, 75 inclusive. Referring to the parts, the numeral 9 indicates heads provided with laterally-spaced depending legs 10, that are formed at their upper portions with vertical slots 11. An anchor-rod 12 is passed through 80 the slots 11 and projects at both ends beyond the legs 10. A coiled spring 13 is attached at its upper end to the intermediate portion of the anchor-bar 12 and at its lower end is attached to the intermediate portion of a short 85 rod 14, the ends of which are seated in notches 15, formed in the lower ends of the legs 10, as best shown in Fig. 5. As shown, three of 90 these spring-cushions are interposed between the leg-section 1 and the socket 6. As 95 shown, the leg-section 1 is provided at its upper end with a metallic band 1^a, that telescopically embraces the lower end of the socket 6. Inward of the band 1^a the leg-section 1 is formed in its annular upper end 100 with seats that receive and fit the exterior surfaces of the legs 10 and permit the same to freely move upward and downward therein. The projecting ends of the anchoring-rods 12 rest upon the upper end of the leg-section 1 105 and fit into slightly-depressed seats 12^a, formed in the upper edge of said leg-section. These shallow seats 16 hold the anchor-rods

12 against endwise movements. When the spring-cushions are thus applied, the lower edge of the socket 6 rests directly upon the heads 9 thereof. As is evident, the springs 5 13 act under tension to yieldingly support said socket 6 and the weight thereon. In practice I have found that tension-springs produce a better yielding action than compression-springs when applied as socket-supports in an artificial limb.

Fig. 6 illustrates a slightly-modified form of the cushion device, in which a cylinder 16 is cast integral with or rigidly secured to the head 9. This cylinder 16 at its upper portion is formed with diametrically opposite longitudinal slots 17, through which the anchor-rod 12 is passed. The lower end of this spring 13 is secured to a cap 18, that is seated in and closes the lower end of the cylinder 16. 15 20 The laterally-spaced parallel legs 10 of the device illustrated in Figs. 2, 3, and 5 may be set any desired distance apart, so that an elastic web of considerable width may be applied to the rods 12 and 14 in lieu of the 25 spring 13.

The several novel features of construction above described have been incorporated in artificial legs and in actual service have been found extremely efficient for the purposes 30 had in view.

What I claim, and desire to secure by Letters Patent of the United States, is as follows:

1. In an artificial leg, the combination with 35 a leg-section having metallic straps secured thereto, of a slip-socket coöperating with said

leg-section and mounted to slide on said straps, and a skeleton, metallic frame and a pliable material, such as buckskin, the former securing the latter in the guide-channels of said slip-socket, substantially as described. 40

2. In an artificial leg, the combination with the lower leg-section, a thigh-socket and jointed thigh-straps connecting the two, of a slip-socket having guide-channels receiving 45 the lower sections of said thigh-straps, the bottoms of said channels having transverse grooves, the skeleton frames, 8 8^a applied in said channels and having their side portions cut away at 8^b, and sheets of pliable material, such as buckskin pressed into said guide-channels by said skeleton frames and projecting into said guide-channels beyond the metallic surfaces of said skeleton frames and engaging with lower sections of said 50 thigh-straps, substantially as described. 55

3. A cushioning device of the character described, comprising a head and a depending slotted body portion, an anchoring-rod projecting transversely through the slot of 60 the said body portion, and a tension-spring applied to the intermediate portion of said anchor-rod and anchored to the lower end of said body, substantially as described.

In testimony whereof I affix my signature 65 in presence of two witnesses.

GUSTAF A. ERICKSON.
